UNITED STATES PATENT OFFICE

SVEND E. JOHANNESEN, OF PITTSFIELD, MASSACHUSETTS, ASSIGNOR TO GENERAL ELECTRIC COMPANY, A CORPORATION OF NEW YORK.

TRANSFORMER.

1,266,480.

Specification of Letters Patent. Patented May 14, 1918.

Application filed December 11, 1915. Serial No. 66,289.

To all whom it may concern:

Be it known that I, SVEND E. JOHANNESEN, a citizen of the United States, residing at Pittsfield, in the county of Berkshire, 5 State of Massachusetts, have invented certain new and useful Improvements in Transformers, of which the following is a specification.

My invention relates particularly to trans- 10 former connection boards.

The connection boards of transformers submerged in cooling and insulating liquids, as oil, are preferably located beneath the surfaces of the liquids, according to the best 15 modern practice. Heretofore, these boards have been placed above the tops of the transformers, in order that they might be readily accessible for changing the connections; commonly, they have been attached 20 to the tops of the transformers.

I have found, however, that in some cases, notably with the smaller transformers, in order to submerge the connection boards, it is necessary to submerge the transformers 25 to greater depths than is required to properly cool the transformers; in other words, in order to submerge the connection boards, more oil (which is the liquid now commonly used) is required than would be required 30 were it not necessary to submerge the connection boards. To contain the extra oil, it is necessary to provide a larger tank than would otherwise be required.

The object of my invention is to avoid the 35 necessity of using unduly large tanks and volumes of insulating liquid to accommodate the connection boards below the liquid level. I accomplish this object by providing peculiarly shaped terminal boards adapted to 40 be, and located, at the sides of the transformers and below the tops thereof. Thus, the liquid depths, and hence the heights, of the tanks may be determined by the heights of the transformers alone; any depths of 45 liquid that submerge the transformers must submerge the connection boards. In order that the connections may be readily changed, I locate the connection boards so that each one is directly accessible through 50 an opening in the tank giving access to the transformer, and preferably I provide suitable connecting members extending substantially parallel to the axis of the tank from the connection boards to a position 55 above the liquid level accessible through

said opening in the tank; in other words, the connection boards are so located that no parts of the transformer over hang the connection boards and thus interfere with direct access to the connection boards 60 through the tank opening.

In the accompanying drawings I have illustrated one form of connection board embodying my invention and shown this connection board located in accordance 65 therewith.

Figure 1 shows the board in elevation, partly in section; Fig. 2 is a plan view of a transformer in its tank and carrying terminal boards similar to that of Fig. 1; Figs. 70 3 and 4 diagrammatically illustrate these connection boards and their relations to the windings of the transformers; Fig. 5 is an elevation of the transformer of Fig. 2, the tank being broken away. 75

As will be seen from Fig. 1, each connection board comprises a body portion 10 of insulating material, provided with two relatively thin, broad extensions 11, one above and one below the body portion, of 80 the same material as the body portion 10. The body portion is provided with three vertical holes 12, 13, and 14, for receiving the terminals and leads. Each connection board is provided with two terminals 85 15, adapted to be attached to winding leads, and a connecting member 18 for changing the connections at the board. The lower end of each terminal 15 is attached to a lead, and the upper end is externally 90 threaded at 21; an annular shoulder 20 is located between the two ends. The annular shoulder 20 cooperates with a shoulder 22 provided in the respective holes 12, 13, and 14 to prevent the terminal from being 95 drawn entirely through the body portion 10, as will be apparent. The threaded portion 21 of the terminal receives a threaded nut 23, both to hold the terminal 15 in position in the body portion 10 of the connecting board and to make necessary connections to this terminal. In certain cases, as illustrated in Figs. 1 and 4, another terminal, in the form of an eye member 27, is engaged with the terminal 15 by being 100 placed around the terminal 15 between the nut 23 and the body portion 10 of the connection board. Washers 28 may be used as desired. The nut 23, it will be observed, is considerably longer than the por- 110

tion of the terminal 15 projecting above the body portion 10 of the connection board. The upper end of this nut 23, as well as its lower end, is internally threaded, and 5 receives in its upper end the threaded metallic portion 29 of the connecting member 18. The upper portion of the connecting member 18 comprises a handle 30 of insulating material. A second eye terminal 31 10 is, in some cases, carried by this member 18 as illustrated; in any desirable way the metallic portion 29 may carry this eye terminal 31 so that the metallic portion 29 may be screwed into and out of the nut 23, 15 electrically engaging and disengaging the eye 31 with the nut 23, without requiring the rotation of the eye 31. As will be observed from Figs. 1 and 5, the connecting member 18 projects above the oil level 20 32 of the transformer tank. The connecting member 18, as is apparent, may be readily disconnected from the terminal 15 in the hole 12, and may be as readily reconnected in the terminal 15 of the hole 14 25 of the same connecting board. It will be observed that the hole 13 of the connection board of Fig. 1 carries no terminal similar to 15, but a lead 33 is carried directly through this hole 13 and is fastened to the 30 eye terminal 31. Which, and how many, holes of the connection boards of this type are supplied with terminals like 15, and also the number and location of the eye terminals like 27 and 31, are, in each case, 35 subject to considerable variation, and are determined by the consideration of the case in hand. Another disposition of the eye terminals is illustrated in Fig. 3, and will be described in detail with reference to this 40 figure.

Connection boards substantially similar to that of Fig. 1 are connected to the sides of their respective transformers, below the tops thereof so that at least the terminals on 45 the connection boards are directly exposed to the surfaces of the oil (or other fluid) submerging the transformers. In other words, the connection boards are so located at the sides of the transformers that unobstructed access to their terminals may be had through the surface of the oil for the purpose of making or changing the connections thereof. The relatively thin, broad projecting portions 11 are provided in order 50 that tape 38 (see Figs. 2 and 5) may be wound around the transformer coils and these projecting portions 11 to attach the connection boards to the coils. In Fig. 2, I have illustrated both the high and low 55 voltage line leads connected to the windings by means of said connection boards; Fig. 5 shows the connections on the low voltage side. The connection boards 39 for the high voltage winding and line leads 40 are similar in all respects to that shown in Fig. 1.

To insulate these boards from the walls of the tank 41, I provide a vertically disposed sheet of insulating material 42 (see also Fig. 5), which is clamped to opposite sides of the core by the clamps 43, and totally incloses the connection boards 39. Such an insulating barrier may, or may not, be necessary, dependent upon the voltages of the terminals and the distance between each connection board and the nearest portion of the tank. The low potential connection boards 44 are substantially like those in Fig. 1; the difference between these boards will be understood from the description of Fig. 3 which follows. The high potential line leads 40 and the low potential line leads 45 pass out of the tank through insulated bushings 46, as heretofore.

The specific connection board which I have illustrated in Fig. 1, and heretofore described, may be slightly varied for making different sorts of connections. Thus, in Fig. 3 I have illustrated the connection board as arranged for use with low potential windings of the smaller transformers, as the leads are now brought from such windings. It will be observed that the low potential winding 50 is provided with two end leads 51 and two tap leads 52, for giving the slight differences in voltages sometimes required. One low potential terminal board is provided for each low potential lead 45, as is also illustrated in Fig. 2. Each connection board comprises two terminal members similar to Fig. 1, located in the holes 12 and 14 as in that figure. The third hole 13 is, however, unoccupied in this case. One of the end leads 51 and the adjacent tap lead 52 are attached to the terminals 15 of one of the connection boards. The corresponding line lead 45 is connected to the eye terminal 27, and this eye terminal is carried by the connecting member 18, as the eye terminal 31 is carried by the connecting member 18 in Fig. 1. It will be observed from this description, and from Fig. 3, that each line lead 45 may be connected to one of the end leads 51 or the adjacent tap lead 52. That is, the connecting member 18, carrying a line lead 45, may be unscrewed from one terminal 15 and screwed into the other, thus changing the connection of the line lead 45 from one end lead 51 to the corresponding tap lead 52, or vice versa.

The high potential winding of the smaller transformers are at present built as two separate halves, as diagrammatically illustrated in Fig. 4. These two half windings, 60 and 61, are either connected in multiple or in series, as the occasion may require. With the high voltage windings, I find it convenient to use the connection board with the parts arranged exactly as shown in Fig. 1. Thus, the high potential leads 40 are at-

tached to the eye connections 27 carried by two terminals 15, one at each connection board; this terminal is, likewise, connected to one end 62 or 63 of one half of the high voltage winding. The opposite ends 64 and 65 of the two halves of the high potential winding are carried to opposite connection boards through the holes 13 therein, as shown. The remaining terminals 15, in each 10 of the two connection boards used, are joined by a conductor 66. Now, it will be apparent that when the connecting member 18 is inserted in the outside terminals 15, as shown in Fig. 4, the two halves 60 and 61 15 of the high voltage winding are connected in multiple. However, as will be understood from Fig. 1, these connecting members 18 may be readily removed from these terminals 15, and, carrying the ends of the 20 leads 64 and 65, may be inserted into the inside terminals 15 joined by the connecting conductor 66. In such an arrangement, it will be apparent that the two halves 60 and 61 of the winding are connected in series. 25 While I have described the principle of my invention, and the best mode I have contemplated for applying this principle, other modifications will occur to those skilled in this art, and I aim in the appended claims to cover all modifications 30 which do not involve a departure from the spirit and scope of my invention.

What I claim as new, and desire to secure by Letters Patent of the United States, is:—

- 35 1. The combination with a tank and a transformer submerged in a liquid in said tank, said tank being provided with an opening giving access to said transformer, of a connection board for terminals of said 40 transformer, attached to a side of said transformer below the top thereof and directly accessible through said opening in said tank.
- 45 2. The combination with a tank and a transformer submerged in a liquid in said tank, said tank being provided with an opening at the top thereof giving access to said transformer, of a connection board, directly accessible through said opening in 50 said tank, attached to a side of said transformer below the top thereof and having terminals of the windings of said transformer exposed thereon, and a connecting member for making various connections 55 with said terminals.
- 55 3. The combination with a tank and a

transformer submerged in a liquid in said tank, said tank being provided with an opening above the surface of said liquid giving access to said transformer, of a connection board attached to a side of said transformer below the top thereof and having terminals of the windings of said transformer exposed thereon, and a connecting member for making various connections 60 with said terminals, said connecting member extending substantially parallel with the vertical axis of said tank from said connection board to a position above the surface of said liquid accessible through said 65 opening in said tank.

4. The combination with a tank, a transformer submerged in a liquid in said tank, and the line leads for one of the windings of said transformer, said tank being provided with an opening above the surface of said liquid giving access to said transformer, of a connection board for each of said line leads at which the terminals of said winding and the line leads are exposed, 75 said connection boards being attached to sides of said transformer below the top thereof, and a connecting member for each of said connection boards for interconnecting said line leads and terminals in various 80 arrangements, said connecting members extending substantially parallel with the vertical axis of said tank from the connection boards to positions above the surface of said liquid accessible through said opening in 85 90 said tank.

5. A terminal board for electrical apparatus comprising an insulating body portion provided with two relatively thin, broad attaching extensions extending from opposite sides of said body portion, and a plurality of terminals carried by said body portion at one of said sides thereof, adapted to be attached to the apparatus leads. 95

6. The combination with a transformer, 100 of a terminal board therefor comprising an insulating body portion provided with a relatively thin portion extending along and taped to a coil of said transformer, and a plurality of terminals carried by said body 105 portion adapted to be attached to the apparatus leads.

In witness whereof, I have hereunto set my hand this seventh day of December, 1915.

SVEND E. JOHANNESEN.
